10 Claims.

(Cl. 292—5)

The present invention relates to a closure fastening device, by means of which it is possible, without touching the window proper, to place the same in a more or less open position for the purpose of ventilation.

An embodiment is described below with reference to the accompanying drawings in which the invention is shown applied to a window of the type mounted to pivot about a horizontal central axis.

In these drawings:

Figures 1 and 1a taken together show a plan of the bottom piece of the window with the ventilation device partially removed.

Figure 2 shows a fragmentary side elevation of that portion of the device illustrated in Figure 1a.

Figure 3 shows a section on line a—b in Figure 1.

Figure 4 shows a section on line c—d in Figure 1.

Figures 5 and 6 and Figures 7 to 12, inclusive, show details.

Figure 13 is a fragmentary perspective view of a window embodying the present invention.

Figure 14 is a similar view of a window having parts broken away to show the operating mechanism.

To the bottom piece of the frame a device is fastened comprising a gear wheel 3 mounted to be rotated on a vertical shaft 2, said gear wheel being fixedly connected to an operating arm 4 and engaging two rods 5, 6, one of which, 5, is positioned at the edge of the gear wheel facing outwards, while the other one is positioned at the inside. The rods 5, 6 are twisted and bent in the way illustrated in Figures 1 and 2 and extend from the centre of the bottom piece of the frame towards the ends thereof. In Figures 1 and 2 just one of said rods is completely shown. At some distance from the gear wheel 3, the rod 6 is provided with a projecting pin 7, extending through a slot 8 of a cover or sleeve 9 enclosing the mechanism.

To the bottom edge of the window-sash 10 a plate 11 is secured opposite the pin 7, said plate 11 being provided with a slot 12 of the configuration shown in Figure 11. The width of said slot is such as to allow the pin 7 to be freely displaced therein. In some cases the slot 12 is of a zigzag-line configuration, as indicated in Fig. 12.

The rod 6 extends somewhat beyond the pin 7 but not so far as to the side piece 13 of the frame. The inner edge of this side piece 13 has a longi-

tudinal recess 14 housing a vertical tube 15, as shown in Figure 1a. Said tube 15 is provided at its lower end with a horizontal arm 16, and said lower end of the tube is positioned in an opening in a plate 17 on the bottom piece of the frame. The arm 16 is provided, at the free end thereof, with a vertical pin 18 engaging a slot 19 of a rod 20 connected in turn with the rod 6 by means of a sleeve 21. Said sleeve 21 encloses the two rods 6, 20 at a portion thereof provided with teeth 22, 23 in the surfaces thereof facing each other, said teeth engaging each other. The arrangements in connection with the rod 5 are of the same nature as those described above in connection with the rod 6.

In the position of the device shown in Figure 1 the window is opened to such extent as to place the open inner end of the slot 12 at the pin 7. When turning the operating arm 4 is a clockwise direction from the position shown in Figure 1, the arm 6 is pulled to the left in Figure 1, the pin 7 thereby sliding on the left-hand edge (Figure 11) of the slot 12, thus forcing the lower part of the window-sash inwards. This continues until the pin 7 enters the outer portion 12a of the slot 12, said portion 12a being parallel to the bottom piece of the frame, and the window-sash then occupying its closed position.

Meanwhile the pin 18 of the arm 16 has been displaced within the slot 19 and at the same time said pin 18 has been swung in a clockwise direction (Figure 1). Simultaneously the tube 15 is turned somewhat in the same direction, and during the movement of the pin 7 in the portion 12a of the slot said tube is pressed against the window-sash 10 so as to create a complete tightening between the frame and the sash.

The upper end of the tube 15 is conveniently inserted in an opening in the top piece of the frame, and as mentioned before, the lower end of said tube is positioned in the opening of the arm 16 and plate 17 but without being fixedly connected to either. By lifting the tube 15 so as to pull it out of the opening of the arm 16 and then moving it obliquely downwards from the top piece of the frame, said tube is easily removed from its position in the frame, this being of importance, as, for instance, when painting.

By the device shown, including toothed rods 6, 20 and the sleeve 21 interconnecting said rods, the total length of the rods is readily varied.

The invention is not limited to employment in windows of the type described but is also advantageously applicable on windows of other types, e. g. windows adapted to pivot about a vertical

axis. Thereby, in certain cases, the tightening tube 15 and the parts nearest connected therewith are superfluous or cannot be utilized advantageously. The invention is not either limited to the construction of details shown in the drawings but all equivalents are also included in the protection.

I claim:

1. In a fastening structure for horizontally pivoted windows, pin and slot connections between the frame and the sash at one of the edges of the window parallel to its pivot axis, a common operating device connected to said pins for moving them towards and from each other, said slots being symmetrically inclined towards each other and of a length to allow the window to be fastened in various open positions, a bar mounted between said frame and sash at the edge thereof perpendicular to the pivot axis of the window, and said bar being rotatable about a longitudinal axis and adapted to be operated by said operating device.

2. A device for fastening an edge of a pivoted window sash to its frame, comprising slotted means on an edge of the sash parallel to the axis of pivoting, said slotted means having a pair of spaced slots therein extending symmetrically obliquely across said edge of the sash whereby the ends of the slots are closer on one side of the sash than on the other, a pair of pins carried by the frame adapted to register with the slots and movable towards and away from each other in a direction parallel to the axis of pivoting of the sash, the walls of each slot being parallel, and means for simultaneously moving said pins towards and away from each other while engaged in the slots for moving said edge of the sash from an open position toward the frame to a closed position and from a closed position away from the frame to an open position, each of said slots having an opening in the end in which the pins are located when the window is in open position to permit removal of the pins from the slots for further opening of the window and to permit entry of the pins into the slots when moving the window toward a closed position.

3. A device for adjustably fastening two relatively movable members, comprising a pair of pins carried by one member spaced apart transversely of the direction of relative movement of the members, the other member having a pair of spaced symmetrical slots formed in a surface parallel to the plane of relative movement and extending obliquely to the direction of relative movement, the leading ends of said slots being open to register with and receive the pins, the walls of each slot being parallel, and means for simultaneously displacing said pins toward and away from each other while in said slots to effect relative movement of said members toward and away from each other, each of said slots having an opening in the end in which the pins are located when the window is in open position to permit removal of the pins from the slots for further opening of the window and to permit entry of the pins into the slots when moving the window toward a closed position.

4. A device for adjustably fastening two relatively movable members, comprising a pair of pins carried by one member spaced apart transversely of the direction of relative movement of the members, the other member having a pair of spaced symmetrical slots formed in a surface parallel to the plane of relative movement and extending obliquely to the direction of relative

movement, the leading ends of said slots being open to register with and receive the pins, the walls of each slot being parallel and means for simultaneously displacing said pins toward and away from each other while in said slots to effect relative movement of said members toward and away from each other, each of said slots having a series of steps provided therein to facilitate fastening of the members in adjusted positions, each of said slots having an opening in the end in which the pins are located when the window is in open position to permit removal of the pins from the slots for further opening of the window and to permit entry of the pins into the slots when moving the window toward a closed position.

5. A device for adjustably fastening two relatively movable members, comprising a pair of pins carried by one member spaced apart transversely of the direction of relative movement of the members, the other member having a pair of spaced symmetrical slots formed in a surface parallel to the plane of relative movement and extending obliquely to the direction of relative movement, the leading ends of said slots being open to register with and receive the pins, the walls of each slot being parallel, and means for simultaneously displacing said pins toward and away from each other while in said slots to effect relative movement of said members toward and away from each other, each of said slots consisting of a series of short oblique portions connected by short portions extending parallel to the direction of movement of the pins, each of said slots having an opening in the end in which the pins are located when the window is in open position to permit removal of the pins from the slots for further opening of the window and to permit entry of the pins into the slots when moving the window toward a closed position.

6. Operation means for pivoted windows, comprising pin and slot connections between the window frame and the window sash at one of the edges thereof parallel to the pivot axis of the window, and a common actuating device in connection with said pins for moving them simultaneously towards and away from each other, said slots being symmetrically inclined and of a length to allow the window sash to be moved in the direction from open position towards closed position by causing the pins to slidably press on one edge of the slots, and in the direction from closed position towards open positions by causing said pins to slidably press on the opposite edge of said slots, each of said slots having an opening in the end in which the pins are located when the window is in open position to permit removal of the pins from the slots for further opening of the window and to permit entry of the pins into the slots when moving the window toward a closed position.

7. Operating means for pivoted windows, comprising pin and slot connections between the window frame and the window sash at one of the edges thereof parallel to the pivot axis of the window, said pin and slot connections comprising two pins and two slots, and a common actuating device in connection with said pins for moving them simultaneously towards and away from each other, said slots being symmetrically inclined and of a length to allow the window sash to be moved in the direction from open position towards closed position by causing the pins to slidably press on one edge of the slots, and in the direction from closed position towards open positions by caus-

ing said pins to slidingly press on the opposite edge of said slots, each of said slots having an opening in the end in which the pins are located when the window is in open position to permit removal of the pins from the slots for further opening of the window and to permit entry of the pins into the slots when moving the window toward a closed position.

8. Operating means for pivoted windows, comprising pin and slot connections between the window frame and the window sash at one of the edges thereof parallel to the pivot axis of the window, said pin and slot connections comprising two pins and two slots, and a common actuating device in connection with said pins for moving them simultaneously towards and away from each other, said slots being symmetrically inclined and of a length to allow the window sash to be moved in the direction from open position towards closed position by causing the pins to slidingly press on one edge of the slots, and in the direction from closed position towards open position by causing said pins to slidingly press on the opposite edge of said slots, the main parts of said slots having rectilinear edges, each of said slots having an opening in the end in which the pins are located when the window is in open position to permit removal of the pins from the slots for further opening of the window and to permit entry of the pins into the slots when moving the window toward a closed position.

5 9. In a fastening structure for pivoted windows, a pin and slot connection between the frame and the sash at one of the edges of the window, an operating device for effecting relative displacement between the pin and slot to cause the window to open and close, a bar mounted between said frame and sash at an edge perpendicular to the edge carrying the pin and slot connection, said bar being rotatable about a longitudinal axis, and means actuated by the operating device for rotating said bar.

10 10. In a fastening structure for pivoted windows, a pin and slot connection between the frame and the sash at one of the edges of the window, an operating device for effecting relative displacement between the pin and slot to cause the window to open and close, a bar mounted between said frame and sash at an edge perpendicular to the edge carrying the pin and slot connection, said bar being rotatable about a longitudinal axis, said operating device having a projection extending along the edge of the window provided with the pin and slot connection, a crank arm carried by said bar, and a pin and slot connection between the end of said crank arm and said projection for transmitting longitudinal movement of said projection into rotary movement of said bar.
